SHOULDER STRAP

Melvin R. James, 2647 S. Dalton Ave., Los Angeles, Calif.

Filed July 27, 1961, Ser. No. 66,090

Term of patent 14 years

(Cl. D3—10)

FIG. 1.

FIG. 2.

FIG. 3.

FIG. 4.

FIG. 1 is a front elevational view of shoulder strap in accordance with the present invention;

FIG. 2 is a side elevational view of the design of FIG. 1;

FIG. 3 is an end view of the design of FIG. 1; and

FIG. 4 is a perspective view of the shoulder strap on a reduced scale as it appears in wearing position. The broken line showing of a container and the partial showing of a wearer are for purposes of illustration only.

I claim:

The ornamental design for a shoulder strap, substantially as shown and described.
